CLAIM

The ornamental design for a thermoelectric band for heating and cooling the skin, as shown and described.

DESCRIPTION

FIG. 1 is an elevational view of the external portion of a thermoelectric band for heating and cooling the skin, showing my new design in open condition;

FIG. 2 is an elevational view of the internal portion thereof, in open condition;

FIG. 3 is a perspective view thereof, in closed position;

FIG. 4 is a side elevational view thereof, in open condition;

FIG. 5 is an end elevational view thereof, in open condition; and

FIG. 6 is an end elevational view thereof, opposite that shown in FIG. 5, in open condition.

The broken line appearing in FIGS. 1 and 3 represent topstitching.

FIG. 1

FIG. 2

FIG. 3

FIG. 4

FIG. 5

FIG. 6
